DESIGN FOR A WRIST FLASHLIGHT

John L. Wyatt, Chicago, Ill., assignor to Rist-beam Corporation, Chicago, Ill., a corporation of Illinois

Application January 18, 1941, Serial No. 98,181

Term of patent 7 years

To all whom it may concern:

Be it known that I, John L. Wyatt, a citizen of the United States, residing at Chicago, in the county of Cook and State of Illinois, have invented a new, original, and ornamental Design for a Wrist Flashlight, of which the following is a specification, reference being had to the accompanying drawing, forming a part thereof.

In the drawing:

light showing my new design.

The dominant features of my design reside in the portions shown in full lines.

I claim:

The ornamental design for a wrist flashlight, substantially as shown and described.

JOHN L. WYATT.
